United States Patent Office

Des. 188,051
Patented May 31, 1960

188,051

ELECTRICAL SWITCH OR SIMILAR ARTICLE

Aime J. Grenier, North Attleboro, Mass., assignor to
Texas Instruments Incorporated, Dallas, Tex., a cor-
poration of Delaware

Filed Sept. 25, 1959, Ser. No. 57,690

Term of patent 14 years

(Cl. D26—13)

Fig. 1.

Fig. 2.

Fig. 3.

Fig. 4.

Fig. 5.

Fig. 1 is a top plan view of an electrical switch or similar article, showing my new design;

Fig. 2 is a front elevational view thereof;

Fig. 3 is a right-hand side elevational view, the opposite side being substantially a mirror image thereof;

Fig. 4 is a bottom plan view thereof; and

Fig. 5 is a rear elevational view thereof.

The dominant features of my new design are shown in solid lines in the drawing.

I claim:

The ornamental design for an electrical switch or similar article, substantially as shown and described.
